UNITED STATES PATENT OFFICE

156,217

DESIGN FOR A VACUUM CLEANER

Thomas Currie, Southport, Conn., assignor to
The Spencer Turbine Company, Hartford,
Conn., a corporation of Connecticut

Application May 3, 1949, Serial No. 2,406

Term of patent 7 years

(Cl. D9—2)

To all whom it may concern:

Be it known that I, Thomas Currie, a citizen of the United States, residing at Southport, in the county of Fairfield and State of Connecticut, have invented a new, original, and ornamental Design for a Vacuum Cleaner, of which the following is a specification, reference being had to the accompanying drawing, forming part thereof.

Fig. 1 is a perspective view of a vacuum cleaner showing my new design.

Fig. 2 is a side view thereof.

Fig. 3 is a front view thereof.

Fig. 4 is a top plan view thereof on a reduced scale.

The dominant features of my design reside in those portions shown in full lines.

I claim:

The ornamental design for a vacuum cleaner, substantially as shown and described.

THOMAS CURRIE.
